[57] **ABSTRACT**

An adjustable trimmer for stripping off the unused edge portions from film strips containing microfilm images of any one of several different widths, for use in making microfiche. The trimmer employs a center cutter roll having the desired width of the microfiche strips, and being removably mounted on one shaft; and a pair of opposed cutter wheels, mounted on a second, parallel shaft, and being spring-biased toward and in cutting engagement with the center cutter roll. One of the cutter wheels is retractable, whereby the center cutter roll can be removed and replaced with another cutter roll of a different, desired width.

VARIABLE FILM-WIDTH MICROFILM TRIMMER**BACKGROUND OF THE INVENTION****1. Field of the Invention**

The present invention relates to the slitting of film and in a preferred embodiment to a variable film-width microfilm trimmer for producing microfiche.

2. Description of the Prior Art

The replacement of one cutter with another identical cutter is known for use when the cutting edges of the first cutter have become dulled. It is also known to use two different trimmers to trim to two different widths.

It is an object of the present invention to provide an apparatus which can be easily changed to trim, from either 16 mm. or 35 mm. microfilm, to any one of a plurality of different microfilm image widths.

SUMMARY OF THE INVENTION

The trimmer of the present invention comprises three separate roll cutters, two outer cutters being on a first shaft and a center cutter being on a second, parallel shaft. The width of the center cutter determines the width to which the film is trimmed. The two outer cutters are biased into contact with the center cutter, one outer cutter is retractable and can be manually pulled out against a spring bias, and the center cutter can be removed from its shaft and replaced with a different center cutter having a different width, after which the retracted roll cutter is allowed to return to its original cutting position. The center roll cutter includes an extension of a particular length that abuts a shoulder accurately located on the second shaft, to accurately align the trimmer with respect to the film strip passing through the trimmer. The distance between the lateral center of each center roll cutter and the end of the extension is the same for all of the different-width, center roll cutters.

BRIEF DESCRIPTION OF THE DRAWINGS

The present invention will be more fully understood by reference to the following detailed description thereof, when read in conjunction with the attached drawings, wherein like reference numerals refer to like elements, and wherein:

FIG. 1 is a partly schematic front elevation view of the apparatus of the present invention; and

FIG. 2 is a partly cross-sectional profile view through the trimming apparatus of FIG. 1.

DETAILED DESCRIPTION OF THE PREFERRED EMBODIMENT

With reference now to the drawings, FIG. 1 shows a preferred overall configuration in which a trimmer 10 of the present invention is used. FIG. 1 is a front elevation view of a trimmer unit 12 comprising a housing 14, a supply reel 16 of microfilm 17 (either 16 mm. or 35 mm.), a take-up reel 18, a guide 20, and the trimmer 10. Both 16 mm. or 35 mm. microfilm reels fit on the unit 12, and the trimmer 10 can trim both 16 mm. and 35 mm. film to any desired width for use in making microfiche, for example, 9 mm., 12.5 mm., and 16.5 mm. are presently preferred widths. The guide 20 is reversible and has a 16 mm. groove in one side thereof, a 35 mm. groove in the other side thereof, and a pair of tongues 22 and 24, one tongue extending from each

end of the guide 20, respectively. The tongues 22 and 24 are positioned between the two grooves, and the groove to be used in placed lowermost, as is shown in FIG. 1, so that the tongues 22 and 24 are above the microfilm strip 17. The tongue 24 adjacent the trimmer 10 extends past the trimmer 10 to prevent the trimmed microfilm strip 25 from tending to curl up around the trimmer 10 and also to guide the microfilm strip 17 in a flat configuration through the trimmer 10 (and particularly when the strip 17 is between a pair of cutter wheels 30 and 32, described below) thereby maintaining constant width of the trimmed microfilm strip 25. There is a tendency for the strip 17 to buckle up or curve up laterally between the cutter wheels 30 and 32 when the cutting edges of the trimmer 10 have become dulled. Other means than the tongue 24 can be used to prevent the strip 17 from buckling or curving up between the wheels 30 and 32. A deflector plate 26 is positioned as shown in FIG. 1 to direct the two trimmed-off edges 27 of the microfilm strip 17 downwardly away from the take-up reel 18.

Reference will now be had to FIG. 2 showing the details of the trimmer 10 itself. The trimmer 10 comprises a pair of opposed, spaced-apart, cutter wheels 30 and 32 and a center cutter roll 34. The cutter wheels 30 and 32 are both loosely mounted on an upper shaft 36. The shaft 36 has a longitudinal groove (not shown) on its surface and each of the cutter wheels 30 and 32 is made to rotate with the shaft 36 by means of a dog point set screw (not shown) inserted through each of the wheels 30 and 32 and into the groove. The wheels 30 and 32 are freely movable axially along the shaft 36 and the wheels 30 and 32 also have a certain amount of rotational "play" about the shaft 36, however, rotation of the shaft 36 forces each cutter wheel 30 and 32 to rotate. The cutter roll 34 is mounted on a lower shaft 38 parallel to the upper shaft 36. The cutter roll 34 is slidably mounted on the lower shaft 38, and is caused to rotate with shaft 38 by means of a pin or key 41 extending from the surface of the shaft 38, which key fits in a slot or groove 43 in the internal bore of the cutter roll 34.

The trimmer 10 is aligned with the guide 20 as follows: the cutter roll 34 is positioned so that the axial center of a cylindrical cutting portion 39 of the cutter roll 34 is in-line with the axis of the guide 20, by accurately locating a shoulder 40 on the lower shaft 38 a predetermined distance from the axis of the guide 20, and by providing the cutter roll 34 with an axial extension 42 projecting from one end of the cutting portion 39, such that the distance between the lateral center of the cutting portion 39 of the cutter roll 34 and an outer edge 44 of the extension 42 (this distance is labelled x in FIG. 2), is equal to said predetermined distance, regardless of what width cutting portion 39 is used. The shoulder 40 is preferably simply the end of one of a pair of locking nuts 46 and 48, threadingly connected to the lower shaft 38, so that the location of the shoulder 40 can be adjusted, if necessary. A thumbscrew 50 screws into a threaded hole in the end of the lower shaft 38 and contacts another axial extension 52 of the cutter roll 34 to hold the cutter roll 34 in place between the thumbscrew 50 and the shoulder 40. The extension 52 is not essential, although it is preferred to make all of the cutter rolls 34 from cylinders of the same length,

and to form the cutting cylinder 39 from the lateral center thereof and to make the extensions 42 and 52 of smaller outside diameter than that of the cutting portion 39. Extensions 42 and 52 have the same length so that the cutter roll 34 can be assembled without specific orientation.

The axially movable or slidable cutter wheels 30 and 32 are spring-biased into contact with the cutter roll 34. A cutting edge 54 of the cutting wheel 32 is urged into cutting contact with a cutting edge 56 of the cutter roll 34 by a spring 58. Similarly, a cutting edge 60 of the cutting wheel 30 is urged into cutting contact with a cutting edge 62 of the cutter roll 34 by a spring 64.

A knob 66 is affixed to the end of the upper shaft 36; the knob 66 is manually grasped, when it is desired to change cutter rolls 34, and is pulled outwardly, thus retracting the upper shaft 36 as well as the outer cutter wheel 30. After the cutter wheel 30 is retracted a sufficient distance, the thumbscrew 50 is removed, the cutter roll 34 removed, a different cutter wheel 34 having a cutting cylinder 39 of the desired width is placed on the lower shaft 38, the thumbscrew 50 replaced, and then the knob 66 and the outer cutter wheel 30 are allowed to return to their normal position. When unscrewing the thumbscrew 50, the spring 58 forces the inner cutter wheel 32 outwardly, however, its outward movement stops when wheel 32 abuts the tongue 24.

The apparatus for rotating the cutter wheels 30 and 32 and the cutter roll 34, and the apparatus rotatably supporting the shafts 36 and 38 form no part of the present invention; the nature of such apparatus is well known to one skilled in the art, and therefore need not be described in great detail. Briefly, the unit 12 includes a pair of vertical support plates 68 and 70 with 30 bearings mounted therein for supporting the shafts 36 and 38. A motor (not shown) is drivingly connected to one of the shafts 36 and 38, and the other shaft is caused to turn by means of a pair of meshing gears 71 and 73 connected to the shafts 36 and 38, respectively. 35 The spring 58 is located between a stationary bearing 72 and the slidable cutter wheel 32, and the spring 64 is located between a stationary bearing 74 and a ring 76 fixed to the upper shaft 36.

While the present invention has been described in 45 detail with respect to the preferred embodiment thereof, the invention can be used for slitting any types of strips for any purpose. Further, other structures can be employed to remove at least one of the two opposed cutter wheels from cutting contact with the cutter roll, whereby the cutter roll can be replaced with another cutter roll of different width. Instead of having the center cutter roll 34 fixed to its shaft 38, it could be axially slidably mounted thereon as are the cutter wheels 30 and 32 whereby only one of the springs 58 and 64 would be needed to urge all three roll cutters into cutting engagement, however, this arrangement would not provide the precision alignment of the above described preferred embodiment.

The invention has been described in detail with particular reference to preferred embodiment thereof, but it will be understood that variations and modifications can be effected within the spirit and scope of the invention as described hereinabove and as defined in the appended claims.

We claim: 1. An adjustable width trimmer comprising:

- a. first and second cutting means for trimming a strip down to a predetermined width;
  - b. means biasing said first and second cutting means into cutting engagement with each other, said second cutting means having said predetermined width to which said strip is to be trimmed;
  - c. means for disengaging at least a portion of said first cutting means from cutting engagement with said second cutting means;
  - d. said second cutting means being removable from said trimmer when said portion of said first cutting means is disengaged, whereby said second cutting means can be replaced by a cutting means having a different width from that of said second cutting means for adjusting said trimmer to trim a strip to said different width;
  - e. said second cutting means being a cutter roll having a cylindrical cutting portion having a pair of opposed cutting edges;
  - f. said first cutting means comprising a pair of cutting wheels, one each of said cutting wheels being spring-biased into cutting engagement with one each of said cutting edges of said cutter roll;
  - g. said cutter wheels being slidably mounted on a first shaft and said cutter roll being removably mounted on a second shaft parallel to said first shaft;
  - h. a knob connected to said first shaft, said first shaft being spring-biased to force said knob into contact with one of said pair of cutter wheels and to force said one cutter wheel into engagement with said cutter roll; said first shaft, said one cutter wheel and said knob all being simultaneously, manually retractable against said spring-bias to disengage said one cutter wheel from said cutter roll a sufficient distance therefrom whereby said cutter roll can be removed from said second shaft and replaced with a different cutter roll;
  - i. means removably holding said cutter roll onto said second shaft; and
  - j. said cutter roll including a lateral extension projecting from one end of said cylindrical cutting portion, said extension being of smaller outside diameter than that of said cutting portion, and the distance between the axial center of said cutting portion and the outer end of said extension being a predetermined distance, and a shoulder positioned on said second shaft for engagement by said outer end of said extension.
2. The apparatus according to claim 1 including adjustment means for adjusting the axial location of said shoulder on said second shaft.
  3. (The apparatus according to claim 10 wherein) An adjustable width microfilm trimmer comprising:
    - a. a center cutting roll including a cylindrical cutting roll having a pair of spaced-apart cutting edge;
    - b. a pair of cutter wheels, one each of said wheels being in cutting engagement with one each of said cutting edges of said cutter roll, whereby the width of said cutting roll determines the width to which a strip of microfilm will be trimmed;
    - c. means for disengaging at least one of said cutter wheels from said cutter roll, whereby said cutter roll can be removed and replaced with a different center cutter roll;
    - d. said pair of opposed cutter wheels being mounted on a first shaft, and said center cutter roll being

removably mounted on a second shaft parallel to and spaced from said first shaft, and means for biasing said cutter wheels and said center cutter roll into cutting engagement with each other; and

e. said second shaft (includes) including a shoulder; said center cutter roll (includes) including an axial extension projecting from one end of said cylindrical cutting portion and having an outside diameter smaller than that of said cutting portion, an outer end of said extension abutting against said

shoulder, and wherein the distance between the lateral center of said cutting portion and said outer end of said extension is a predetermined distance.

4. The apparatus according to claim 3 wherein said 5 biasing means includes a pair of springs, one each of said spring biasing one each of said cutter wheels toward said center cutter roll.

5. The apparatus according to claim 3 including 10 means for coupling said shafts together for rotation.
